METHOD OF AND MEANS FOR TWISTING

Leslie James O'Dowd, Drummondville, Quebec,
Canada, assignor to Celanese Corporation of
America, a corporation of Delaware

Application August 21, 1931, Serial No. 558,475

3 Claims. (Cl. 117—26)

This invention relates to method of and means for twisting yarns or threads and relates more particularly to the production of yarns or threads of high twist and of relatively fine denier or of low tenacity by means of a flyer or analogous twisting device.

An object of my invention is to twist yarns in a very economical and efficient manner. A further object of my invention is to provide means for employing a flyer twisting device to impart high twist to yarns of fine denier and/or low tenacity. Other objects of my invention will appear from the following detailed description.

When attempts are made to twist yarns made of artificial filaments and particularly yarns of fine denier by means of a flyer twister, it has been found that the yarns tend to break or be damaged so that so many interruptions in the operations occur and so much supervision is required that the twisting operation by means of a flyer cannot be carried out with complete commercial success. I have found that this is due to the fact that in previous apparatus for flyer twisting, the guide eye for the yarn leaving the flyer has been placed vertically above the axis of the vertical spindle upon which the supply or winding-off bobbin is mounted and this results in the yarn being subjected to such strain during the twisting process that frequent breakages or other damages to the yarn occur. I have discovered that if such guide or centering eye is placed at some distance away from the line extending vertically from the axis of such spindle, a great deal of the strain or tension on the yarn is eliminated, so that it is possible to twist artificial yarns of fine denier and/or low tenacity by a flyer process efficiently and at low cost.

In accordance with my invention I twist yarn by drawing yarn at a suitable linear speed from a supply bobbin or other package that is mounted on a rapidly rotating spindle that is equipped with a flyer or similar acting device through which the yarn passes, and then causing the same to pass through a point that is spaced from a line that is an extension of the axis of the spindle of the take off package, prior to winding the yarn onto the take up bobbin or package.

This invention is applicable for imparting twist of any degree, but is particularly suited for imparting high twist to yarns for making so-called "crepe yarns" such as are used for the preparation of crêpe de Chine, georgette, crepe marocain, etc.

While this invention is applicable to the twisting of yarns of all kinds whether made of natural fibres or of artificial filaments, it is particularly

applicable for the twisting of yarns of fine denier and/or low tenacity made of artificial filaments particularly cellulose acetate or other organic derivatives of cellulose such as organic esters of cellulose and ethers of cellulose. Examples of other organic esters of cellulose are cellulose formate, cellulose propionate and cellulose butyrate while examples of ethers of cellulose are ethyl cellulose, methyl cellulose and benzyl cellulose. This invention is also useful for the twisting of yarn made of reconstituted cellulose such as may be made by the viscose, cuprammonium or Chardonnet process. Composite yarns of various kinds, as for example yarns combining cellulose acetate or other synthetic yarn and natural silk or other natural fibers, or yarn combining two or more synthetic fibers may be twisted by my process.

The centering eye through which the yarn passes may be displaced in any direction, that is to say, the yarn may be caused to pass in front of a line drawn through the axis of the twisting spindle, or behind it, or to the left of it or to the right of it, or in any other position not on the direct line passing through the axis of the twisting spindle. As to the extent of displacement of the centering eye from the normal position, this depends on circumstances and is governed by the distance of the centering eye from the spindle, the denier of the yarn, the weight of the flyer, and the tension which it is desired that the yarn should sustain in twisting. In practice the required distance is determined by a trial under actual working conditions, the centering eye or its support being moved until the desired tension is obtained.

The displacement of the guide or centering eye to a position which is not vertically above the winding off spindles results in the reduction of the excessive tensions normally developed in flyer twisting so that by my invention breakage of yarns is substantially completely eliminated, and accordingly makes possible the commercially successful twisting of fine denier yarns of cellulose acetate or other fine denier artificial yarns or other yarns of low tenacity by a flyer process,—a result heretofore impossible. By my invention fine denier cellulose acetate yarns can be twisted by a flyer process very efficiently and at low cost. Fine denier mixed yarns containing cellulose acetate and silk or other natural fibres can be twisted by my process with less suspensions of operation and with remarkably high efficiency.

In order further to illustrate my invention but

without being limited thereto reference is had to the accompanying drawing, wherein

Figure 1 is an elevation partly in section showing my invention as applied to a flyer twisting device, and

5 Figure 2 is a cross section along the line 2—2 of Figure 1 showing the centering eye.

On the drawing the supply bobbin 1 is mounted on the rotating vertical spindle 2 and the yarn 10 Y is drawn from the bobbin 1 through the flyer 3 and the centering or guide eye 4 located in a special manner, as will be explained later, to the take up or winding bobbin 5. While a "figure 8" flyer is shown on the drawing, this invention is 15 applicable to the use of other flyers, such as the "figure 4" flyer, the 2 arm straight flyer, or the Universal flyer. The bobbin 5 is driven by the rotating cork roller 6 which engages its surface frictionally and the yarn is guided onto this bobbin by means of the traverse guide 7 on the traverse bar 8.

In order to reduce the rather excessive stresses 20 on the yarn produced by the ordinary arrangement of the prior flyer twisting device, I place the centering or guide eye 4 at a point which is laterally of the line extending vertically from the axis of the spindle 2 of the take off bobbin 1. By placing the centering eye 4 in this position 25 rather than vertically above the spindle 2, the stresses and strains on the yarn being twisted 30 are greatly reduced so that the great advantages pointed out above may be attained. The centering eye 4 is mounted on a rail 9. In order to permit the necessary displacement of the centering 35 eye 4, the rail 9 may have a slot 10 at its point of support and the bolt 11 passes through this slot to permit the securing of the rail in the desired position.

In operation the take off or supply bobbin 1 40 is rotated at the required high speed, while the yarn Y is being drawn off by the take-up bobbin 5. This rotation of the bobbin 1 with the assistance of the flyer 3, imparts twist to the yarn in the course of its passage from the supply 45 bobbin to the take-up bobbin, as is well understood. The centering eye 4, being displaced from a line extending vertically from the spindle 2, causes the yarn to pass through the flyer in such a manner that it is not subjected to such great 50 stresses and strains as it would be if it were conducted, after leaving the flyer, through a point vertically above the spindle 2, so that the fine denier yarns or yarns of low tenacity may be twisted economically and with great efficiency by 55 means of the flyer twisting device.

It is to be understood that the foregoing detailed description is given merely by way of illustration and that many variations may be made therein without departing from the spirit of my invention.

Having described my invention, what I claim and desire to secure by Letters Patents is:

1. Process of twisting yarn which comprises drawing yarn of fine denier and containing cellulose acetate filaments from a package rotating 10 at a relatively high speed, passing said yarn through an unwinding device which is movable under the influence of tension in the yarn and is adapted to assist the twisting and to guide the yarn to a point above said package, which point 15 is substantially in a line passing through and coincident with the vertical axis of the package, and then causing the yarn to pass, from said device to a winding device, in an angular path through a fixed point which is spaced from said 20 line passing through the vertical axis of the package.

2. Apparatus for twisting yarn comprising a rotating vertical spindle adapted to support a 25 yarn package from which the yarn is drawn off, a winding device adapted to wind the yarn whereby twist is imparted to the yarn, unwinding means, movable under the influence of tension in the yarn, for assisting the twisting of the 30 yarn and for guiding said yarn to a point above said spindle, which point is substantially in a line passing through and coincident with the vertical axis of said spindle, and a guide for the 35 yarn between the last named means and the winding device, said guide being placed at a fixed point spaced from said line passing through the vertical axis of the spindle whereby the yarn is caused to travel in an angular path from said 40 twisting means to said winding device.

3. Apparatus for twisting yarn comprising a 45 rotating vertical spindle adapted to support a yarn package from which the yarn is drawn off, a winding device adapted to wind the yarn whereby twist is imparted to the yarn, a flyer mounted on said spindle, means on said flyer for guiding said 50 yarn to a point above said spindle, which point is substantially in a line passing through and coincident with the vertical axis of said spindle, and a guide for the yarn between the flyer and the winding device, said guide being placed at a fixed point spaced from said line passing through the vertical axis of the spindle whereby the 55 yarn is caused to travel in an annular path from said flyer to said winding device.
